FIG. - 1

FIG.-2

FIG -3

INVENTOR:
EDWIN CHALENBURG
BY Whiteley and Ruckman
HIS ATTORNEYS

UNITED STATES PATENT OFFICE.

EDWIN CHALENBURG, OF STARBUCK, MINNESOTA.

STORE-FIXTURE.

1,356,694.

Specification of Letters Patent. Patented Oct. 26, 1920.

Application filed August 25, 1919. Serial No. 319,772.

To all whom it may concern:

Be it known that I, EDWIN CHALENBURG, a citizen of the United States, residing at Starbuck, in the county of Pope and State 5 of Minnesota, have invented certain new and useful Improvements in Store-Fixtures, of which the following is a specification.

My invention relates to store fixtures and an object is to provide a device having compartments varying progressively in size for containing articles which come in different sizes. A further object is to provide a device having two sets of related compartments, each compartment in one set corresponding to a compartment in the other set. In this manner articles which come in different sizes and have two separate parts may be kept in stock and readily selected according to the desired size without likelihood of the wrong size for either part being handed out.

The full objects and advantages of my invention will appear in connection with the detailed description thereof, and the novel 25 features embodied in my inventive idea will be particularly pointed out in the claim.

In the accompanying drawings which illustrate the application of my invention in one form,—

30 Figure 1 is a top plan view of the device; Fig. 2 is a front elevational view; Fig. 3 is a view of the device in section on the line 3—3 of Fig. 1.

35 Referring to the particular construction shown in the drawings my invention comprises a supporting structure preferably of wood having a back 10, ends 12 and 14, a bottom 16, and a horizontal partition 18. The bottom 16 and the horizontal partition 40 18 are wider adjacent the end 14 than they are adjacent the end 12 so that their front edges are inclined relatively to the back 10 as will be seen from Fig. 1. The purpose of 45 this is in order that a plurality of compartments gradually increasing in size may be provided both above and below the partition 18. The upper compartments 20 are made of sheet metal and are cylindrical in shape 50 with vertical slits 22 at the front. The edges of the slits of adjacent compartments are secured together by vertical strips 24,

the edges of which are turned down over the edges of the material forming the slits. The two end strips are secured to the ends 55 12 and 14 by any suitable fasteners, such as nails 26, and one or more of the compartments may be secured in suitable manner to the back 10, as by nails 28. A strip of metal 30 secured to the top of the partition 18 has its front edge turned up at 32 and secured to the bottom edges of the strips 24. Lower compartments 34 are formed between the bottom 16 and the partition 18 by vertical partitions 36 while pieces 38 are secured 60 over the partitions to form front walls for the compartments, these walls stopping short of the top and having slits 40 extending vertically midway of the compartments. 65

70 The operation and advantages of my invention will be readily understood from the foregoing description. My device is shown in use for containing different sizes of pump leathers. The plunger packings *a* are placed in the proper compartments 20 according to size and the flat valve members *b* are placed in proper compartments 34 according to size. Both sets of compartments are constructed so that the particular size of 75 leathers will snugly fit therein. When the compartments are refilled with a new supply it is easy to judge by the fit whether the leathers are being placed in the proper compartment. In the case of pump leathers the 80 valve members are somewhat larger than the corresponding plunger packings, but the compartments for the valve members are placed for the greater part underneath the corresponding compartments for the plunger packings. If desired, a label indicating the size may be placed adjacent each compartment. It is obvious that my device 85 may be used for articles other than pump leathers. The articles in both sets of compartments are retained in place but may be readily removed by lifting the uppermost 90 one of any stack as desired to the top of the compartment.

95 I claim:

100 A store fixture comprising a support having a bottom which gradually increases in width from one end to the other, a plurality of hollow cylindrical members of sheet ma-

terial mounted in a longitudinal row on said support and forming compartments which gradually increase in size corresponding with the increase in width of said bottom,
5 the walls of said compartments at the front being provided with vertical slits to facilitate the removal of articles from the com-

partments, and vertical strips of sheet material securing the edges of the slits of the adjacent compartments.

10

In testimony whereof I hereunto affix my signature.

EDWIN CHALENBURG.
